UNITED STATES PATENT OFFICE.

THOMAS S. BENNETT, OF ATTLEBORO, MASSACHUSETTS

BAND FOR BRACELETS.

No. 870,076.

Specification of Letters Patent.

Patented Nov. 5, 1907.

Application filed May 29, 1907. Serial No. 376,276.

To all whom it may concern:

Be it known that I, THOMAS S. BENNETT, a citizen of the United States, residing at Attleboro, in the county of Bristol and State of Massachusetts, have invented certain new and useful Improvements in Bands for Bracelets, of which the following is a specification, reference being had therein to the accompanying drawing.

My invention relates to that class of bands for bracelets which are of the lazy tongs type and is an improvement of the structure set forth in my former United States Patent No. 709,195.

The essential objects of my present invention are to produce a more firm, secure, and cheap union of the parts which shall have a slight appearance; and to form the back side of the band in such a manner as produce a smooth, unbroken surface. The rear surface of bands as at present made have joints into which the perspiration from the arm penetrates and soils the gold, and in case of gold plated goods, coacts with the brass to stain the gold and flesh.

To the end of securing the enumerated advantages, my invention consists in the novel construction and combination of parts hereinafter set forth, and illustrated in the accompanying drawings, wherein,

Figures 1 and 2 are rear and side elevations respectively of a front arm shell. Figs. 3, 4 and 5, side elevations of the parts inclosed within a front arm. Fig. 6, a rear elevation of a complete front arm. Figs. 7 and 8, rear and side elevations respectively of a back arm shell. Fig. 9, a side elevation of rear plate of a back arm. Fig. 10, a like elevation of one of the back arm plates. Fig. 11, a rear elevation of a complete back arm. Figs. 12 and 13 are rear and side elevations respectively of a complete unit. Figs. 14 and 15, sections of the same on lines $x-x$ and $y-y$ respectively of Fig. 13. Fig. 16, an elevation of the rear of the novel band complete, and Fig. 17, an elevation of the rear of the old form of band.

Like reference characters indicate like parts throughout the views.

A convenient embodiment of my novel band comprises a plurality of units arranged in a lazy tongs series, each unit comprising a front arm, A, and back arm, B, pivoted to each other at their centers. These arms may inclose springs as hereinafter set forth, or the springs may be located outside the arms as shown in United States Patent No. 782,188, it being immaterial to the purposes of this invention what, if any, spring mechanism is employed.

The arm, A, comprises a shell or cover, a , cupped up from a thin metal blank of precious or plated metal, having its inner margin cut away to form a flange, a' , and shoulder, a^2 . Upon opposite sides of the shell, a , the flange, a' , is transversely cut or sawed at two points as a^3 , thereby producing independent flange portions,

a^4 opposite each other midway the length of the shell. When the spring means of my former patent is used in the arm, A, the arched plate, C, shown in Fig. 3 is inserted in the shell, a ; said plate being provided with 60 the notch, c , and carrying the tubular pivot, c' . The plate, C, rests against the back plate, D, shown in Fig. 4. The latter is provided with tubular rivets, d , upon its end with which to pivot the ends of the front of one unit to the back arm of the adjacent unit. 65 The plate, D, has also an opening formed by a collar, d' , midway its length, through which passes the pivot, c' , and a spiral spring, E, one of whose ends, e , registers in the notch, c , and whose other end, e' , extends within the back arm. The back or retaining plate, 70 D, is held in position by bending over upon its margin the flanges, a^4 , as shown in Fig. 6. The flange, a' , is folded inwardly upon itself with its edge resting upon the shoulder, a^2 , as shown in Fig. 15, by which means the raw edge is concealed or obviated and a smooth 75 precious metal surface only exposed. The flanges or ears, a^4 , are concealed by the back arm now to be described.

The back arm, B, comprises a shell, b , of plated stock, provided with a flange, b' , shoulder b^2 , and ears 80 b^4 , produced by cuts, b^3 , all similar to the corresponding parts of the shell, a . A plate, F, shown in Fig. 10 provided in its ends and center with rivet openings, f , to engage the rivets, d , and pivot, c' , is placed within the shell, b . The back or retaining plate, G, of the 85 back arm is shown in Fig. 9. It is provided with a central opening, g , into which passes loosely the sleeve, d' , and this opening is preferably surrounded by a tubular extension, g' . The plate, G, has also an integral marginal flange, g^2 which may be omitted if the 90 stock of the plate is thick, and end perforations, g^3 . The plate, G, is fixed in position by pressing the ears, b^4 , inwardly and downwardly upon its margin. The flange, b , is folded upon itself, as shown in Fig. 15, with its edge resting upon the shoulder, b^2 . In assembling the parts the end, e' , of the spring, extends within 95 the arm B and presses against the side wall of the shell, b .

The assembled units, as shown in Fig. 16, present an unbroken surface to the flesh, and thus avoids the 100 disadvantages inherent in old seamed structure shown in Fig. 17.

The spring, E, it should be understood, is omitted in a majority of the units.

What I claim is,

1. A lazy-tongs band composed of pairs of arms pivoted to each other at or near their centers, each pair of arms comprising first, a front arm comprising a plate provided with pivots upon its ends and an intermediate opening, an outside shell provided with a marginal flange folded upon itself, ears upon the shell engaging the plate, and second, a back arm provided with means for receiving said pivots.

2. A lazy-tongs band composed of pairs of arms pivoted to each other at or near their centers, each pair of arms comprising first, a front arm provided with pivots upon its ends, and second, a back arm comprising a plate adapted to receive the pivots, and having an intermediate opening, an outside shell, provided with a marginal flange folded upon itself, and ears upon the shell engaging the plate.
3. A lazy-tongs band composed of pairs of arms pivoted to each other at or near their centers, each pair of arms comprising first, a front arm comprising a plate provided with pivots upon its ends and an intermediate open-

ing; an outside shell provided with a marginal flange folded upon itself, ears upon the shell engaging the plate; and second, a back arm comprising a plate adapted to receive the pivots and having an intermediate opening, an outside shell provided with a marginal flange folded upon itself, and ears upon the shell engaging the plate. 15

In testimony whereof I have affixed my signature in presence of two witnesses.

THOMAS S. BENNETT.
